UNITED STATES PATENT OFFICE.

DELA NO D. DUNKLEE, OF NORTHAMPTON, MASSACHUSETTS.

DESIGN FOR A CARD-MOUNT FOR PHOTOGRAPHS.

SPECIFICATION forming part of Design No. 34,638, dated June 11, 1901.

Application filed May 10, 1901. Serial No. 59,708. Term of patent 7 years.

To all whom it may concern:

Be it known that I, DELANO D. DUNKLEE, of Northampton, in the county of Hampshire and State of Massachusetts, have invented and produced a new and original Design for Card-Mounts for Photographs, of which the following is a specification, reference being had to the accompanying drawings, forming part thereof.

10 This invention is a design for a card-mount for photographs, of which the following is a specification, reference being had to the accompanying drawings, forming a part thereof.

15 In the drawings, Figure 1 is a plan or elevation of the front of the card, and Fig. 2 is a section on line 2 2 of Fig. 1.

20 The invention or design consists in a rectangular card *a*, having in its center a slightly-depressed plane surface *b*, oval in shape, on which the photographic print is to be placed, an oval bead or embossment *c*, surrounding the plane surface *b*, a depressed plane surface *d*, surrounding the oval bead *c* and

formed with its outer edges parallel with the edges of the card *a*, and a plane surface *e*, 25 surrounding the plane *d* and having its outer edges respectively parallel to the outer edges of the surface *d* and at substantially the same distance from the latter, the plane of the surface *e* being slightly lower than that of the 30 outer portion of the card, but higher than that of the surface *d*.

The dividing-lines between the depressed and elevated surfaces *d e* are sharply defined, and the combination of an oval surrounded 35 by rectangles produces a very artistic effect as a mounting for photographic pictures.

I claim—

The design for a card-mount for photographs, substantially as shown and described. 40

In testimony whereof I have affixed my signature in presence of two witnesses.

DELANO D. DUNKLEE.
